UNITED STATES PATENT OFFICE.

CHARLES A. MELCHERT, OF KANSAS CITY, MISSOURI, ASSIGNOR, BY MESNE ASSIGNMENTS, TO THE ACCIDENT INSURANCE MACHINE COMPANY, OF KANSAS CITY, MISSOURI, A CORPORATION OF THE TERRITORY OF NEW MEXICO.

COIN-CONTROLLED VENDING-MACHINE.

1,014,016.

Specification of Letters Patent.

Patented Jan. 9, 1912.

Application filed January 8, 1909. Serial No. 471,313.

To all whom it may concern:

Be it known that I, CHARLES A. MELCHERT, a citizen of the United States, residing at Kansas City, in the county of Jackson and State of Missouri, have invented certain new and useful Improvements in Coin-Controlled Vending Machines; and I do declare the following to be a full, clear, and exact description of the invention, such 10 as will enable others skilled in the art to which it appertains to make and use the same, reference being had to the accompanying drawings, and to the letters and figures of reference marked thereon, which 15 form a part of this specification.

My invention relates to a coin controlled vending machine and more particularly to a machine for delivering time stamped tickets after the insertion into the machine of 20 a suitable coin.

It is the object of my invention to provide a machine comprising a number of successively operating parts, such as a time stamp, a ticket feeder, and ribbon forwarding and reversing mechanisms, which, while performing their functions individually are so combined and arranged that their operations take place in a proper sequence, together with a single coin controlled driver 25 from which the various parts are actuated, and clock set type wheels for coöperating with the stamping device.

A further object of my invention is to provide other parts necessary for the proper 30 operation and control of a machine of this character.

In the accompanying drawings, I have illustrated my preferred form of each of the structures which combine to form the 40 complete machine, and have illustrated the preferred combination and arrangement of such parts.

In the drawings, to which reference is made by like numerals in the specification 45 to—

Figure I is a view in elevation of a coin controlled vending machine constructed according to my invention. Fig. II is a front view of the operative parts of the machine. 50 Fig. III is a side view of same. Fig. IV is a plan view of same. Fig. V is a side view of same on the line V—V, Fig. IV. Fig. VI is a rear view of the coin controlled clutch mechanism. Fig. VII is a

side view of the same parts, on the line 55 VII—VII, Fig. VI. Fig. VIII is a sectional view of same on the line VIII—VIII, Fig. II. Fig. IX is a sectional view of same on the line IX—IX, Fig. VI. Fig. X is a longitudinal section of the crank shaft. 60 Fig. XI is a detail view, partly in section, of the coin controlled clutch on the crank shaft. Fig. XII is a longitudinal section of the coin receptacle. Fig. XIII is a detail view of one of the clutch disks (line 65 XIII—XIII, Fig. XI). Fig. XIV is a similar view of the other clutch disk (line XIV—XIV, Fig. XI). Fig. XV is a detail view of the clutch trip. Fig. XVI is a longitudinal section of the ticket feeding 70 mechanism, on the line XVI—XVI, Fig. IV. Fig. XVII is a cross section of the same parts on the line XVII—XVII, Fig. XVI. Fig. XVIII is a side view of the cam for actuating the ticket feeder mechanism (line XVIII—XVIII, Fig. XXI), one of the cam keepers being removed for better illustration. Fig. XIX is a sectional view of the pitman and lever on the line 75 XIX—XIX, Fig. XVI. Fig. XX is a sec- 80 80 tional view of the pitman and roller on the line XX—XX, Fig. XVI. Fig. XXI is a sectional view of the pitman and cam on the line XXI—XXI, Fig. XVI. Fig. XXII is a side view of the ticket feed- 85 85 ing pawl (line XXII—XXII, Fig. XVII). Fig. XXIII is a central vertical section of the ticket forwarding slide and its draw back mechanism. Fig. XXIV is a plan view of the type wheel parts. Fig. XXV 90 is a vertical section of same on the line XXV—XXV, Fig. XXIV. Fig. XXVI is a side view, partially in section, of the time controlled, type-wheel operating mechanism. Fig. XXVII is a side view of 95 the full set of type wheels. Fig. XXVIII is a side view of the "5 minute wheel" and its controlling mechanism (line XXVIII—XXVIII, Fig. XXV). Fig. XXIX is a side view of the stationary member which 100 is interposed between the day and week wheel, and of the week wheel (line XXIX—XXIX, Fig. XXV). Fig. XXX is a front view of the stamping and ribbon actuating mechanism. Fig. XXXI is a sectional view 105 of the ribbon drum and drum actuating parts on the line XXXI—XXXI, Fig. XXX. Fig. XXXII is a plan view of the cam and

lever mechanism for reversing the ribbon carrying parts. Fig. XXXIII is a central vertical section of the stamp post parts. Fig. XXXIV is a rear view of the stamp post actuating cam. Fig. XXXV is a sectional view of the post dog and cam disk on the line XXXV—XXXV, Fig. XXXIV. Fig. XXXVI is a sectional view of the clock and type wheel setting mechanism on the line XXXVI—XXXVI, Fig. III. Fig. XXXVII is a sectional view of same on the line XXXVII—XXXVII, Fig. XXXVI. Fig. XXXVIII is a plan view of the type wheel adjusting mechanism. Fig. XXXIX is a sectional view of the clock shaft equalizing mechanism, on the line XXXIX—XXXIX, Fig. XXXVIII. Fig. XL is a view of a time stamped ticket. Referring more in detail to the parts:—

in order to provide a convenient receptacle for coins received into the machine, I prefer to support the case 1, within which the machine parts are contained, upon a hollow pedestal 2, the respective ends of which are flared to form the floor base 3 and the machine base 4. Within pedestal 2 is a bracket 5 into which a coin tube 6 is adapted to project, the bracket being provided with downwardly opening, tortuous, hanger slots 7, and the tube with pins 8 which are adapted for projection into such slots and support on the slot seats, as illustrated in the front view of such parts, Fig. II.

9 designates a coin chute which extends through the base 10 of the machine case and terminates within the collar 5, and 11 a door in the side of the pedestal through which access is had to the coin tube and through which said tube may be hung and removed.

Referring now to the machine parts, 12 designates the main driving shaft, which is journaled in bearings 13—13' in the machine frame.

14 designates a crank shaft, which extends through the machine case, preferably near the front, and is journaled at its inner end in the machine frame.

Rigidly mounted on the respective shafts 12 and 14 are the gear wheels 15—16, which constantly mesh with each other and through which the drive shaft is actuated from the crank shaft, as will be hereafter described.

17 designates a sleeve which is revolvably mounted on the outer end of the crank shaft and turns in a box 18 in the machine case, such sleeve being projected into the machine case a sufficient distance to carry a spreading collar 19, a spur wheel 20, and a clutch collar 21, the wheel and clutch collar being rigidly mounted on the sleeve 17 and the wheel partially projected into a slot 22 in the coin chute 9. At its outer end sleeve 17 carries a crank 23, the hub of which is preferably attached to the collar by a set screw 24.

Rigidly mounted on the crank shaft 14, and abutting against the clutch collar 21 and inner end of sleeve 17 is a drum 25, which is partially cut away to form an outer disk 26 and inner cam 27.

28 designates a bridge which unites, and is preferably formed integral with the disk and cam and is grooved at 29 to contain a clutch slide 30, such slide being adapted to project at its outer end into a socket 31 in the clutch collar 21 and be engaged by the edge of such socket.

33 designates a cup on the cam 29, the chamber of which registers with the slide groove 29 and is adapted for receiving the end of the clutch slide 30, a spring 34 being located in the slide chamber and adapted for normally tensioning the clutch slide in the direction of the collar socket.

35 designates a dog on the clutch slide which is beveled on its outer face to provide an inclined surface for engagement with the beveled edge of a trip lever 36, which is pivoted to the machine frame at 37, and has a projecting lever arm 38. Also pivoted to the machine frame is a friction lever 39, the arm 40 of which is rigidly connected with the arm 38 of lever 36, while its upper arm 41 is projected into the coin chute 9 opposite the spur wheel 20, sufficiently to engage a coin descending in the chute and support same between its inner surface and the spurs on said wheel.

42 designates a spring which is preferably carried on the coin chute and is adapted for constantly yieldingly tensioning the lever arm 41 in the direction of the chute slot.

43 designates a pin on the clutch lever 36 which is adapted for constant engagement with the periphery of the cam 27 and held yieldingly toward its cam engagement through the action of the friction lever spring 42.

44 designates a lever which is pivoted to the machine frame and has an arm 45 that projects into the coin chute in position to hold a descending coin directly above the teeth of the spur wheel 20, and a beveled arm 46 which is adapted for engagement with a pin 47 on the clutch collar, the pin 47 being so arranged in relation to the slide socket 31 that the lever 44 is rocked by the pin 47 at the proper movement to release the clutch slide and enable it to seat in such socket.

Under normal conditions the crank sleeve 12 will, when the crank is actuated, revolve idly on the crank shaft. When a coin is inserted through the opening 9', it descends in the chute 9 and is held by the lever arm 45 until the arm 46 is engaged by the pin 47 and the lever is rocked and the cam released. The coin then engages the revolving spur wheel and is moved downwardly thereby, forcing the friction and clutch levers outwardly to release the slide 30 and 130

enable same to be projected into the socket 31, the clutch lever being held out of engagement with the slide by the cam 27. With the crank sleeve and shaft united by 5 the clutch, the machine is operated, during a single complete revolution of the crank, and as the revolution nears its completion the pin on the clutch lever moves over the step on the cam and causes the beveled lever 10 arm to move back into engagement with the clutch slide, the slide being moved back out of its clutch socket as the drum revolves and causes the beveled edge of the slide to impinge against the beveled edge of the clutch 15 lever. With the slide back in its original position the connection between the crank sleeve and shaft is broken and the crank may revolve idly as before.

Referring now to the type-wheels, 50 designates the type wheel shaft and 51 a spring shaft to which and to a spring drum 52 the 20 clock spring 53 is rigidly attached, the type wheel and spring shafts being operatively connected through the gearing 54—55—56 25 and 57.

58 designates a key shank on the shaft 51, 59 a ratchet on said shaft, and 60 a spring pressed pawl which is adapted for co-operation with the ratchet 59.

30 Revolubly mounted on shaft 50 is a type-wheel 61, the rim of which is provided at regular intervals with raised numeral type, beginning with the numeral 5 and running in multiples of five to the numeral "55" and 35 terminating in "—", to indicate five minute spaces throughout an hour. Also rigidly mounted on shaft 50, adjacent to and connected with wheel 61, is a control disk 62. Extending alternately in opposite directions 40 from the periphery of the disk 62 are the teeth 63, 63' which are adapted for engagement with the teeth 64—64' of escapement levers 65—65' which are revolubly mounted on a shaft 66, carried by the machine frame.

45 67 designates an escapement shaft which is revolubly mounted in the machine frame and has operative connection with a clock shaft 68 through the gearing 69 and 70. Rigidly mounted on the escapement shaft 67 is a 50 double disk 71—71', the members of which are provided with the rim notches 72—72' which are arranged at regular intervals in the disk peripheries and alternate regularly throughout the circumference of the members, each of said notches having a straight 55 radial side and an inclined side, as illustrated. On each of the escapement levers is a back tooth 73—73' which is adapted for engagement with the disk periphery and for 60 retreat into the disk notches, the levers being influenced toward the disks by their own weight and by the tension of the control wheel teeth against the lever teeth 64—64'. It is readily apparent that one of the levers 65 will always be in a position to hold the con-

trol wheel while the other is back within the notched disk, and that the alternate position of the levers will permit a regular beveled movement of the control disk. The disk members 71—71' are so arranged that 70 the escapement levers alternate in their control disk engagement every five minutes and the control and "5 minute wheel" allowed to move one space at each recurrence of that interval.

75 designates a type wheel, the hub 76 of which is revolubly mounted on the shaft 50, the rim of the wheel being provided at regular intervals throughout its circumference with numerals running from 1 to 12, which 80 are adapted to represent hours of the day. Mounted on the hub 76 and rigidly connected with the wheel 75 is a spur wheel 77. Revolubly mounted in the machine frame is a shaft 78, which carries a loose sleeve 79, 85 and rigidly mounted on sleeve 79 is a spur wheel 80 which meshes with the wheel 77 on the hour type wheel. Also rigidly mounted on shaft 78 is a star wheel 81, the points of which are adapted for engaging 90 a pin 82 that is carried by the "5 minute" wheel 61 and control wheel 62.

Rigidly mounted in the machine frame and extending parallel with the shafts 78, 95 50 and 67 is a shaft 83. Pivoted at one end on shaft 83 is a pawl 84, the free end of which is adapted for engagement with and projection between the points of the star wheel 81.

85 designates a spring which is connected, 100 at one end, with a cross bar 86 on the machine frame and at the opposite end with the pawl 84, so that the latter yieldingly holds the star wheel in a set position when such wheel is inert and tensions same against 105 the beveled portions 87 of the wheel points when the wheel is in motion, the lines of force being such that the wheel will be held by the pawl except when moved against the tension of the spring by the pin 82.

110 The parts just described are so arranged and combined with the clock and main spring that once every five minutes the escapement acts to release the "5 minute" wheel to the action of the main spring, and 115 at each revolution of the "5 minute" wheel the hour wheel is moved through a single interval, through the action of the star wheel and gearing 80 and 71.

Revolubly mounted on shaft 50 is the hub 120 88 of a third type wheel 89, the rim of which bears, at regular intervals and in proper sequence throughout its circumference, the word types Sunday A. M., Sunday P. M., Monday A. M., Monday P. M., etc., the 125 name of the day, or an abbreviation thereof, appearing twice in succession, followed by the noon insignia. Mounted on the hub 88 and rigidly connected with the wheel 89 is a spur wheel 90 which meshes with a spur 130

wheel 91 rigidly mounted on the shaft 78. Rigidly mounted on shaft 78 is a star wheel 92, the points of which are adapted for engagement by a pin 93 on the hour wheel 75. 5 94 designates a pawl which is pivoted at one end on the shaft 83 and is adapted for engagement at its opposite end with and projection between the points of the star wheel 92, a spring 95 connecting the pawl and star 10 86 so that the wheel 92 is held in the same manner and for the purpose mentioned relative to like parts in the "5 minute" wheel combination. It is apparent that with this mechanism the star wheel 92 will be moved 15 upon each full revolution of the hour wheel 75, and the day wheel moved one interval with the movement of the star wheel 92.

100 designates a large type wheel which is preferably of greater diameter than those 20 previously mentioned, and mounted on an independent shaft 101, one tangent of the wheel being in the plane of the other type wheels in order to provide a horizontal stamping face for the ticket, as will presently be described. The rim of wheel 100 bears at regular intervals throughout its circumference, numeral types which run consecutively from 1 to 52, and are intended to 25 designate the number of the weeks in a 30 year.

102 designates a spur flange on the hub of wheel 100 which meshes with a spur wheel 103 which is rigid on a collar 104, revolvably mounted on the shaft 78. Also rigid on 35 collar 104 is a star wheel 105, the points of which are adapted to engage a pin 106 on the week wheel 89. 107 designates a pawl which is pivoted at one end on the shaft 83 and is adapted for engagement at its opposite end with and projection between the 40 points of the star wheel 105, a spring 108 connecting the pawl and bar 86 so that the wheel 105 is held in the same manner and for the purpose mentioned relative to the 45 parts in the "5 minute" and hour wheel combinations. It is apparent that with this mechanism the star wheel 105 will be moved upon each free revolution of the day wheel 89, and the week wheel moved one interval 50 with the movement of the star wheel 105.

Between the week and day wheels, I preferably fix a rail 109 from which the type word "week", or an abbreviation thereof, is projected, so that when the machine is 55 first set, the successive wheels will read 12-5-Sun. A. M.-wk-1, denoting that it is the twelve-five-Sunday morning the first week of the year.

A more detailed description of the type 60 wheels and their operation will be given after the description of the remaining features of the machine.

Referring now to the ticket feeding parts, 115 designates an open bottom 65 ticket bin, which is located above and

slightly to the rear of the type wheels and is adapted for containing a stack of tickets 116 of suitable size and thickness. Bin 115 is supported on the rails 117 which extend longitudinally in the machine and form the 70 upper members of a ticket slide chute 118, the lower members of which are the rails 119, the rails 117 being cut away within the bin to enable the stack of tickets to rest on the lower rails 119 and the bottom ticket to 75 be moved between the upper and lower rails when it is forwarded from the bin, as will presently be described. Below and parallel with the slot 118 is a slot 120 within which a slide 121 is adapted to travel. Slide 121 is 80 provided with slots 122 near its forward end, through which the arms 123 of the pawls 124 are adapted to project, the pawls being pivoted to the slide and provided with the weighted arms 125 which tension the 85 arms 123 upwardly into their ticket engaging position while allowing same to be turned back when engaged by the bottom of the under ticket in the bin, during the return travel of the slide. 90

126 designates a tape which is attached to the end of the slide 121 and is run over a pulley 127 at the rear of the machine frame to be attached to a spring drum 128, by 95 which the slide is yieldingly held in and returned to its set position.

129 designates a lever which is pivotally mounted on the machine frame and 130 a link which pivotally connects the free end of said lever with the slide 121. Pivotally 100 mounted on the lever 129, near its mounting, is a pitman comprising the side members 131 which are connected at their forward ends with the lever pin 132 and provided at their back ends with the slots 133. 105

134 designates a pin which connects the pitman side members and carries a roller 135 by which said members are spread.

Journaled in the machine frame and having operative connection with the driving 110 shaft 12 through the gearing 136-137, is a cam shaft 138 which projects through the slots 133 in the pitman members.

139 designates a cam which is carried by the shaft 138 and is adapted for engagement with the roller 135, the cam having one rounded edge and one flat edge with curved corners and being attached to its shaft, near one end, to provide an eccentric as well as a cam action in its operation. 115 120

When the parts are inert, the slide, lever, and cam parts are in the position indicated in full lines, Fig. XVI. When the shaft 12 is turned, the roller 135 is engaged by the cam swell and moved forwardly, forwarding 125 the ticket slide, through the lever and link connection, the pawls 124 engaging the rear edge of the bottom ticket in the bin and causing a forward ticket feed. As the shaft 12 continues to revolve, the cam swell is 130

5 moved past the roller and the latter moves onto the flat cam face, when the spring drum 128 acts to draw the slide, lever, and pitman back to the position indicated in dotted lines, Fig. XVI, the dogs 124 yielding downwardly as they engage the under face of the bottom ticket in the bin and, after leaving such contact, engaging the rear edge of the bottom ticket. As the 10 shaft 138 is moved through the remainder of its revolution, the short end of the cam again moves the roller forwardly to its original position and forwards the ticket a short distance in its slot, the clutch in the crank shaft 15 being broken when the parts have assumed this position, and the parts being allowed to remain in such position until a succeeding operation.

20 Referring now to the stamping mechanism, 140 designates a vertical shaft which is revolutely mounted in the machine frame and is operatively connected with the shaft 12 by gearing 141—142.

25 143 designates a post bracket, 144 a post which is adapted to slide vertically in bracket 143 and in a portion of the machine frame, and 145 a dog on said post which is adapted for engagement with a lifting cam.

30 146 designates a stamping head which is rigidly mounted on the lower end of the post 144 and extends horizontally above the line of type wheels, previously mentioned, 147 a pad on the striking face of head 146, and 148 a compression spring which surrounds the post 144 and bears against the collar of the stamping head and within a socket 149 on the portion of the machine frame upon which the post bracket is mounted, and yieldingly tensions the stamping head toward the type wheels.

35 150 designates a spring which surrounds the upper portion of the post 144 and bears against the upper portion of the post bracket and against the under face of a collar 151 on said post, the spring 150 being weaker than the spring 148 and adapted to lift the post and stamp head slightly, after the spring 148 has expended its force in the down stroke of the stamp.

40 50 Journaled in the post bracket and in a bearing 152 on the machine frame is a shaft 153, which is operatively connected with the vertical shaft 140 by gearing 154—155. Rigidly mounted on the shaft 153 is a disk

55 156, the face of which carries a boss 157 that is adapted for engaging the under side of the dog 145 and lifting the post upon the revolution of disk 156. The stamping parts are so constructed and combined with the 60 main driver that the shaft 153 will make two complete revolutions and the stamp act twice for each single revolution of the main drive shaft 12 and crank 23.

158 designates hangers which are suspended from the machine frame and carry

drum shafts 159. Rigidly mounted on the shafts 159 are the ribbon drums 160, upon which the inked ribbon 161 is carried, the ribbon being fixed at opposite ends to the drums 160 and run over the top type wheels 70 so that it will rest between the wheels and ticket when the stamp acts and cause a record to be made on the under face of the ticket, rollers 160' being suspended from the hangers 158 in position to guide the ribbon 75 in its travel over the type wheels.

In order to feed the ribbon between the drums, I provide a sliding bar 165 which is adapted to reciprocate in the machine frame and is provided with pawls 166—167, one 80

of which is adapted for engagement with its ratchet during the forward travel of the ribbon and the other with its ratchet during the travel of the ribbon in the reverse direction, the inert pawl being held out of engagement with its ratchet by a keeper 168—169 which is rigidly mounted on the reciprocating bar and comprises leaves which straddle the ratchets. To actuate the bar 165, I provide the rocking lever 170, the 85

body of which is pivoted, near one end, to the machine frame, and connected at its opposite end with the reciprocating bar. The lever body has the arms 171—172 which straddle the vertical shaft 140 and are 90

adapted for engagement by the dog 173 which is rigidly mounted on said shaft. With such parts the shaft dog 173 engages both of the arms 171—172 upon each revolution of the shaft so that the bar 165 is 95

moved backwardly and forwardly with each complete revolution of the shaft, dropping the operative pawl to allow it to engage a ratchet tooth and lifting same to move the drum one space, the opposite drum 100

being revolved by the pull of the ribbon to allow the ribbon to pay out therefrom. To reverse the ribbon travel, I provide the bar 175 which is mounted on the drum shafts, the bar having the slots 176 at its ends to 110

permit projection of the drum shafts therethrough, the ends of the bar being adapted for engagement with the studs 177 on the pawls 166—167, so that either of the pawls may be moved back to its inert position according to the position of the bar 175.

Pivoted to the machine frame is a T-lever 178, to the cross arm 179 of which is pivoted a link 180, that is provided with a slot 181 through which a pin 182 on the ribbon reversing bar 175 is projected. The cross arm 184 of lever 178 is provided with a weight 185 which is heavy enough to throw the bar 175 in either direction when the lever is moved off of center.

186 designates a worm wheel which is revolutely mounted on the machine frame and has operative connection with a worm 187 on the main driving shaft 12. Pivotally connected with the body arm 188 of le- 130

ver 178 is a link 189, which extends down over the face of wheel 186 and has a slot 190 through which the worm wheel pin 191 is projected.

5 In operation, the worm 187 turns the wheel 186 until the link 189 is moved upwardly or downwardly a sufficient distance to throw the weighted arm of the T lever off center, when the weight drops the lever 10 and moves the shifting bar to release one of the ribbon drum pawls to its operative position and move the opposite pawl to its inert position, the worm wheel being continuously operated during the operation of 15 shaft 12 and preferably gaged to allow the ribbon to run from end to end before being reversed.

In order to constantly maintain the proper combination between the clock and 20 type wheels, I have provided the following mechanism for connecting the clock shaft 68 with the clock parts. 200 designates the clock mechanism, which may be of any suitable construction and is provided with the 25 shaft 201, the forward end of which is journaled in a bearing adjacent to the clock face. 202 designates the hand shaft which projects through the clock face and has the minute hand 203 rigidly mounted thereon, the shaft 30 202 being connected with the clock shaft 201 by gearing 204—205. Loose on the hand shaft 202 is a sleeve 206 which projects through the clock face and carries the hour hand 207. 208—209 designate twelve to one 35 gear wheels which are fixed on the clock shaft and sleeve respectively and are adapted for moving the sleeve through one revolution for every twelve revolutions of the clock shaft. 210 designates a shaft which is 40 operatively connected at its upper end with the clock shaft 201 through the gearing 211—212, and at its lower end is provided with a worm wheel 213 which is adapted to seat in a case 214 rigidly mounted on the upper end of the type wheel clock shaft 68. 215 designates a worm which is revolvably mounted in case 214 and is adapted for turning the worm wheel and shaft 210, for the purpose of bringing the clock hands and 45 type wheels to their proper relative position.

216 designates a lid on the case 1 through which access may be had to the machine parts.

Inasmuch as the machine may be properly 55 divided into two sets of working parts, one operative from the clock mechanism and the other from the crank shaft, I will first describe the operation of the time controlled parts, as they operate continuously irrespective of the stamping, ticket feeding and like devices, which are controlled from the crank mechanism.

Assuming the type wheels and clock 60 mechanism to be working in unison and the type wheels to be set for the first week of the

year, Sunday A. M., and 12 o'clock, a ticket stamped at that time will be marked as indicated in Fig. XL, all of the wheel parts remaining in their set position because of the holding action of the escapement lever 70 65 against the teeth on the control disk 62; such lever being held in its tooth engaging position by the rim of the disk 71. As the clock mechanism moves the shaft 67, a rim notch in the disk 71 is moved beneath the 75 back tooth on the lever 65 and the lever rocked by the tension of the control disk until the tooth 63 is free therefrom and the disk allowed to revolve until a succeeding tooth is engaged by the opposite escapement 80 lever 65', which has been moved out to its tooth engaging position by the escapement disk member 71'. As the control disk is rigidly connected with the "5 minute" wheel and the teeth 63 are set to correspond with the markings on such wheel, the type wheel is moved around one space with the partial revolution of the control disk, so that the marking 10 is brought into the stamping position to indicate on a ticket that it is 10 85 minutes after twelve o'clock on Sun. A. M., the first week of the year. The "5 minute" wheel is operated in this manner, once every five minutes until even hour, when the pin 82 on the "5 minute" wheel and control disk 90 engages one of the points on the star wheel 81 and moves such wheel and the collar 79 through a partial revolution against the tension of the spring 85. Upon the revolution of the collar 79, the gear wheel 80, which is 95 rigid on the collar, moves therewith and causes a partial revolution of the gear wheel 77 which is rigidly connected with the hour type wheel 75, the star wheel 81 and gear wheels 80 and 77 being so constructed that 100 with each actuation by the pin, on the control disk, the hour type wheel is moved through a single space which, in the present instance, carries the numeral 1 from under the stamping position and moves the numeral 2 thereunder, so that should a ticket be printed immediately after the change of the wheel, the even second hour will be indicated thereon. The hour type wheel 75 is 105 provided with a pin 93, similar to the pin 82 110 on the "5 minute" wheel, which is adapted for engagement with the points of a star wheel 92 that is rigid on the shaft 78 and is adapted for actuating the gears 91 and 90, which latter is rigid with the day type wheel 89, so that at each complete revolution of the hour wheel 75 the day type wheel will 115 be moved one space. As the hour wheel is divided into twelve equal spaces, it will make two complete revolutions every twenty-four hours, and actuate the day wheel twice, during that period, so that, in the present instance, the first movement of the hour wheel will move the portion of the day wheel bearing the marking Sun. A. M., 120 125 130

- from under the stamping position and move that portion, bearing the marking Sun. P. M., into the stamping position. Each consecutive revolution of the hour wheel has 5 a like effect, so that the proper day of the week may always be indicated on the ticket. The pin 106 on the day type wheel in turn actuates the star wheel 105 and gears 103 and 102 to move the week wheel 100 an interval at each complete revolution of the day wheel. As the wheel 100 is marked from 1 to 52 consecutively, it is apparent that when the day wheel has been moved around until the marking Sun. A. M. is again 10 in the stamping position, that portion of the wheel 100 bearing the numeral 2 will be in alignment with the markings on the other type wheels and the proper record printed across the ticket.
- 20 Should the clock be allowed to run down, and it become necessary to set the clock hands, the type wheels may be simultaneously set to their proper stamping position through the gear connections with the hand shaft 206 and the clock shaft 201, which latter is connected with the "5 minute" type wheel through the shafts 210, 68 and 67, and the escapement mechanism, previously described.
- 30 Under normal conditions, the crank 23 is loose on its shaft 14, so that it may be turned without affecting the ticket stamping and feeding parts. When a coin is placed in the chute opening 9', it descends in the chute 9 until it is caught by the lever arm 45 and supported thereby until the lever arm is rocked through the engagement of the pin 47 on the collar 20, with the inner lever arm 46. When the coin is released from the lever arm it drops into contact with the teeth on the wheel 20 and with the inner face of the lever 41, when a continued revolution of the crank will force the coin down through the slot and move the lever 41 outwardly.
- 45 Upon the actuation of the lever 41, the lever 36 is rocked until it contacts with the slide 29 and such slide is projected inwardly by the spring 33 until its free end seats in the socket 31 in the collar 26, which is rigid 50 with the crank sleeve, forming a rigid connection between the shaft 14 and the crank sleeve, which will produce an actuation of the shaft upon the actuation of the crank, such parts remaining locked until the shaft 55 and the drum 25 have completed a revolution and the pin 36' on the lever 36 has passed over the cam step on the disk 27, and the lever 36 is moved back by the spring 42 into its dog engaging position. Upon the 60 return of the lever 36, the slide is engaged thereby and moved back against the tension of the spring 33, breaking the contact between the crank sleeve and shaft 14, so that the former will move idly on the latter and 65 not affect the ticket parts.

The ticket feeding parts are so arranged that the forward end of a ticket is over the stamping line of the type wheels while the machine is inert and the stamp is set, so that immediately upon the actuation of the 70 shaft 12 by the crank shaft 14, the cam 157 on the shaft 153 will release the dog 145 on the stamp post, and the stamp be shot downwardly against the ticket by the spring 148, such spring expending its force before 75 the stamp engages the ticket, so that the weaker spring 150 may raise the stamp body slightly to permit the feeding of the ticket, as will presently be described. When the stamp strikes the upper surface of the ticket 80 the latter is forced against the ribbon and the type wheels causing the latter to print through the ribbon onto the face of the ticket. As soon as the stamp has been raised out of its ticket contact, the feeding parts 85 operate to move the ticket forwardly, until a second or coupon portion of the ticket is over the stamping line of the type wheels. During the feeding of the ticket the stamp is raised by the engagement of the cam 157 90 and dog 145 until, when the ticket has come to rest in its second stamping position, the stamp is again released to produce a second stamping operation, the two operations producing identical printed lines on the ticket 95 body and coupon. After the second stamping operation the post 144 is raised, so that the springs 148 and 150 remain tensioned and the cam 157 and dog 145 ready to release the stamp immediately upon a succeeding 100 operation of the crank shaft.

Referring now to the ticket feeding parts:—As soon as the stamp has descended for its first operation, the cam 134 engages the roller on the pitman 131 and moves the 105 lever 129 forwardly against the tension of the spring drum 128, the pawls 124 moving the ticket into its second position. The parts are so arranged that when the ticket assumes its second position the cam 134 will 110 have moved around until the roller 131 passes over the curved side of the cam so that the lever may be drawn back by the spring drum 128, the roller passing over the flat side of the cam to the position indicated in dotted lines Fig. XVI. While the lever is being drawn back, the dogs 124 are held depressed until they pass over the rear end of the bottom ticket in the bin 115, when they are elevated by their weight arms, so that 115 their forward edges may engage the rear edge of the bottom ticket in the pile, which is dropped down to rest on the rails 119 when the previous ticket has been forwarded from the bin. Upon a continued operation 120 of the crank and shaft 138 the pitman 131 is again forwarded slightly, causing the lever 129 and dogs 124 to move forwardly beneath the ticket, the dogs pushing the bottom ticket before them, until such ticket is 130

in its first stamping position over the type wheels, the previously printed ticket being moved by the succeeding ticket into the delivery chute 118' through which it is delivered to the purchaser. All of the parts are now in a position for the printing and delivery of the last named ticket upon the succeeding insertion of a proper coin.

Inasmuch as the ribbon feeding and releasing mechanisms have been described hitherto, and their operation is obvious, I will not specifically describe the operation of these parts.

Having thus described my invention, what I claim as new therein and desire to secure by Letters Patent is:—

1. The combination with a ticket feeding mechanism of a printing mechanism, a driving shaft, connection between the driving shaft and feeding mechanism, and connection between the shaft and the printing mechanism, embodying a hammer, means tending to force the hammer to printing position, means for holding the hammer from printing position, and gearing between the driving shaft and hammer holding means adapted for twice releasing said hammer and returning same to its held position with each complete operation of the driving shaft.
2. The combination with a ticket feeding mechanism, of a printing mechanism, a driving shaft, connection between the shaft and feeding mechanism, and connection between the shaft and printing mechanism comprising a hammer and hammer post, a spring tending to force the hammer to printing position, a dog on the hammer post, a rotatable shaft having a boss normally engaging said post dog to hold the hammer against the tension of its spring, and gearing between said rotatable shaft and drive shaft whereby the rotatable shaft is moved through two complete revolutions upon each single revolution of the drive shaft, for the purpose set forth.
3. The combination with a ticket feeding mechanism, of a printing mechanism, a driving shaft, connection between the driving shaft and feeding mechanism, and connection between the driving shaft and printing mechanism comprising a hammer and hammer post, a striking spring tending to force the hammer to printing position, a spring adapted to partially lift the hammer

after the actuation by said striking spring, a dog on the hammer post, a rotatable shaft having two to one gear connections with the driving shaft, a disk on said rotatable shaft, and a boss on said disk adapted for engagement with the post dog, substantially as and for the purpose set forth.

4. The combination with a ticket feeding mechanism, of a printing mechanism, a driving shaft, connection between said shaft and printing mechanism, and connection between said shaft and ticket feeding mechanism embodying a lever, a cam adapted for actuation from the driving shaft and adapted for producing a plurality of actuations of said lever during each complete operation of the driving shaft, and means for returning said lever to a set position after each cam action.

5. The combination with a ticket feeding mechanism, of a printing mechanism, a driving shaft, connection between the driving shaft and printing mechanism, and connection between the driving shaft and feeding mechanism embodying a rocking lever having yielding means tending to hold it from the printing mechanism, a rotatable cam shaft, and a cam eccentrically mounted on said shaft and adapted for producing a plurality of actuations of said lever during each operation of said driving shaft.

6. The combination with a ticket feeding mechanism, of a printing mechanism, a driving shaft, connection between the driving shaft and printing mechanism, and connection between the driving shaft and feeding mechanism embodying a rocking lever having a spring whereby it is yieldingly held from the printing mechanism, a cam shaft, and a cam, having a flat and a concaved side, eccentrically mounted on said shaft and adapted for actuating said lever, said connection being adapted to first forward the lever against the spring tension, then return the lever by the spring tension, and finally forward said lever and retain same in its forwarded position.

In testimony whereof I affix my signature in presence of two witnesses:

CHARLES A. MELCHERT.
